DESK PAD

Charles Goldstein, Chicago, Ill.

Application May 20, 1942, Serial No. 443,713

4 Claims.

(Cl. 120—24)

This invention relates to improvements in desk or blotter pads of the kind used on writing desks, and has for its principal object to provide a more durable, superior article of manufacture of the character described.

Desk pads have heretofore usually consisted of a sheet of fibrous material, suitably bound with fabric or leather, and having fabric or leather pockets along opposite sides or at the corners to receive the edges or corners of a sheet of blotting material.

In carrying out my invention, I provide a blotter pad having its base member made of a sheet of fibrous material such as cardboard, but covered by a relatively thin, resilient sheet of metal, clamped securely over the edges of the cardboard and having its upper surface suitably finished so as to provide a relatively hard, yet semi-yielding surface particularly adapted for writing. The device is preferably provided, however, with blotter-holding pockets, so that a blotter sheet may be used with the pad, if desired.

I also provide an improved form of marginal pocket-forming panel for use with a base pad of the character described, wherein said panel may be interchangeable arranged either as a simple decorative edging for the blotter pad, or as a holder for memo pads, calendars or similar accessories removably mounted in said panels. Other novel features of my invention will appear as the following description proceeds.

The invention may best be understood by reference to the accompanying drawings, in which

Figure 1 is a perspective view of one form of desk pad constructed in accordance with my invention.

Figure 2 is an enlarged detail section taken on line 2—2 of Figure 1.

Figure 3 is a detail section taken on line 3—3 of Figure 1.

Figure 4 is a perspective view showing a modified form of my invention, including interchangeable marginal panels used in connection therewith.

Figure 5 is a detail view of a solid panel member adapted for use with the form of desk pad shown in Figure 4.

Figure 6 is an enlarged detail section taken on line 6—6 of Figure 4.

Figure 7 is an enlarged fragmentary detail view, in perspective, of the panel construction shown in Figure 4.

Figure 8 is a perspective view showing a novel form of individual panel members for providing blotter-holding pockets and especially adapted

to be applied to a base member to replace other panel members which have become worn out or unserviceable.

Figure 9 is a detail section taken on line 9—9 of Figure 8.

Figure 10 is the same as Figure 9 with base board inserted.

Referring to details of the embodiment of my invention illustrated in Figures 1 to 3, the desk or blotter pad is indicated generally at 10 and comprises a flat base board 11 of the usual rectangular form having panels 12, 12 attached at opposite ends thereof. As shown more in detail in Figures 2 and 3, the base board consists of a sheet of fibrous material 13, such as cardboard, covered by a sheet of metal 14 having flanged margins 15 bent downwardly over the margins of the cardboard and clamped over and along the latter, so as to secure the two sheets together as a unit.

The metal sheet 14 is much thinner than the cardboard sheet 13, being preferably of 30 gauge or less, in order to give the desired resilient characteristics to the exposed upper surface of the base board, as will presently be described in detail. Said metal sheet may be of copper, steel, brass or any similar material. If the metal used is subject to corrosion, its upper surface is plated or otherwise covered with a suitable protective coating such as enamel or the like. In practice, I find that it is usually preferable to provide the upper surface with a smooth semi-lustrous finish, either of the metal itself or by a suitable coating simulating a metallic finish, in order to enhance the appearance and attractiveness of the pad as an article of furniture.

The panels 12, 12 shown in Figures 1 and 3 consist of elongated pocket members including an upper panel facing 16 having its outer and end edges 17 folded over and beneath the edge of the base board 11 and suitably secured to the under surface thereof, as indicated in Figure 3. A sheet of felt 18 may be secured to the under face of the base board 11 in the usual manner to complete the structure.

A base board formed of a flexible sheet covered with a thin metal sheet as above described, affords an especially desirable writing surface due to its smooth and yet semi-yielding characteristics. Because of its superior qualities in this respect, it is preferable in most instances to omit the use of a covering sheet of blotter material such as is usually employed with desk pads of ordinary construction. However, when a sheet of blotter material is desired, it can be inserted

as usual with its opposite edges enclosed in the pockets beneath the panel facings 16, 16.

My metal covered base board also renders the writing pad much more durable than ordinary pads. Moreover, the arrangement whereby the marginal edges 15 of the metal covering are bent under and clamped along the marginal edges of the fibrous sheet 13 effectively prevents any permanent buckling or distortion of the exposed surface of the base board which otherwise is likely to occur where heavier sheet metal is employed in a device of this character.

Referring now to the form of desk pad shown in Figures 4, 5, 6 and 7, the base board 11 consists of a fibrous sheet 13 and metal covering sheet 14 constructed and arranged in the same manner described in connection with the previous figure. In place of the pocket type panels 12, 12, however, I provide interchangeable panel structures 19, each consisting of an elongated metal sheet 20 having parallel side edges 21, 21 turned upwardly and inwardly as shown in Figure 6 so as to form opposed overhanging shoulders to serve as a holder for receiving interchangeably either a filler piece 22, or detachable memo pads, calendars or similar accessories. In Figure 4 one of the holders 19 is shown with a strip of cardboard 23 inserted endwise therein, bearing a calendar for a full year thereon, while the other holder has a pad of paper, indicated at 24, inserted therein for use as a memo pad in the usual manner. It will be understood, of course, that such calendars and memo pads are interchangeable with each other, or if desired, one or both can be entirely removed from their holders by sliding them endwise, and filler pieces 22 can be inserted in lieu thereof, as indicated in dotted lines in Figure 4. The filler pieces 22 can be made of various materials and colors so as to assist in matching the desk pad with other articles of furniture to be used therewith.

The holders 19 may be applied to the base board 11 in any suitable manner, as for instance by rivets 25, 25, spaced from the inner edges of said holder, so that the latter edges overhang the base board to form a blotter-receiving pocket.

Figures 8, 9 and 10 illustrate a novel form of panel member 26 which may be made up as individual units for attachment to a base board such as the member 11 previously described in connection with the foregoing figures. Each of such panel members 26 consists of an upper facing 27 and a lower facing 28 connected thereto along one edge and opposite ends to form, in effect, an open pocket. The lower facing 28, however, has an extension 29 integral therewith. This extension is preferably provided with a covering of adhesive material, as for instance it may include a sheet of gum cloth secured thereto as indicated

5 at 30 in Figures 9 and 10. The panel member 26 is, of course, adapted for application to the base board 11 when the desk pad is initially manufactured, but this particular type of panel member is especially advantageous in order to replace panels which have been previously used with a base board, but have been worn out or damaged while in service. Accordingly, when a worn out panel is to be replaced, it is removed from the base board, and the substitute panel member 26 can be readily attached in its place by inserting the edge of the base board in the pocket and securing the extension 29 to the bottom face of the base board (or to the felt sheet, if such is used) by means of the adhesive material carried by the sheet of gum cloth on said extension 29. I find that my novel form of metal covered base board is so much more durable and longer lasting than ordinary base boards, that the panels often wear out long before the base board. Accordingly these new panel members 26 may be employed to prolong the life of the desk pad when necessary.

20 Although I have shown and described certain embodiments of my invention, it will be understood that I do not wish to be limited to the exact construction shown and described, but that various changes and modifications may be made without departing from the spirit and scope of my invention as defined in the appended claims.

25 I claim as my invention:

1. As a new article of manufacture, a desk or blotter pad including a base board consisting of a sheet of fibrous material covered with a thin sheet of metal of 30 gauge or less, having its edges bent under and clamped along the edges of said fibrous sheet to form a unitary board structure having a semi-yielding upper writing surface.

30 2. In a desk or blotter pad, a base board, a panel member comprising a plate secured along the edge of said base board and having upturned parallel edges forming opposed grooves for interchangeably receiving a plurality of filler members in endwise sliding engagement therein.

35 3. In a desk or blotter pad, a base board, a panel member comprising a plate secured along the edge of said base board to form a blotter-sheet pocket therebetween, and having upturned parallel edges forming opposed grooves for interchangeably receiving a plurality of filler members in endwise sliding engagement therein.

40 4. A panel member for desk pads, comprising a detachable, relatively flat pocket member having an extended bottom wall, and adhesive material carried on said extended bottom wall adapted for securing said panel member along the edge of a desk pad.

45 CHARLES GOLDSTEIN.
